HAIR WAVING PROTECTOR

William H. H. Davis, San Francisco, Calif., assignor to United States Appliance Corporation, San Francisco, Calif., a corporation of California

Application July 3, 1934, Serial No. 733,581

3 Claims. (Cl. 132—36.1)

This invention relates generally to the construction of protectors such as are employed in the waving of human hair.

In the so-called permanent waving of human hair, it has become common practice to utilize protectors which are clamped upon the strands of hair, adjacent the scalp. In croquignole waving, where the curlers extend parallel to the scalp, each protector generally consists of two elongated parts hingedly connected together and which can be tightly clamped together by suitable locking means. Such protectors usually perform two important functions, namely, to protect the scalp against undue heating during the steaming or baking operation, and to grip the hair strand sufficiently tightly to prevent pull being transmitted to the scalp when the hair is tensioned upon the overlying curler.

With protectors as they have been constructed in the past, particularly for croquignole waving, the gripping surfaces are formed by strips of resilient rubber, forming a permanent part of the structure. Such rubber strips are subject to rapid deterioration, due to the temperatures to which they are subjected and also by virtue of contact with chemical solutions. Such deterioration results in a loss of the desired grip upon the hair strand, thus rendering the entire protector inefficient or worthless for further use.

It is an object of the present invention to provide a protector of the type described above, which can be maintained in efficient condition over a long period of time. As will be presently explained, the parts or members of the protector forming the resilient gripping surfaces can be readily removed for replacement or for reversal, in order to present new and unused gripping surfaces.

Further objects of the invention will appear from the following description in which the preferred embodiment of the invention has been set forth in detail in conjunction with the accompanying drawing.

Referring to the drawing:

Fig. 1 is a plan view illustrating a protector incorporating the present invention, the two parts of the protector being swung apart.

Fig. 2 is a view similar to Fig. 1, showing the manner in which the hair-gripping members can be removably applied to the remainder of the device.

Fig. 3 is a cross-sectional detail taken along the line 3—3 of Fig. 1.

Fig. 4 is an enlarged side elevational view, partly

in cross-section, illustrating a suitable construction for each of the resilient gripping members.

Fig. 5 is a cross-sectional detail taken along the line 5—5 of Fig. 4.

Fig. 6 is a cross-sectional detail, similar to Fig. 5, but showing a modified construction.

The protector as illustrated in the drawing consists of two elongated elements or parts 10 and 11, which are hingedly connected together and which are adapted to be clamped upon opposite sides of a strand of hair. The part 10 is formed of a relatively rigid bar 12 to which an overlying metal plate 13 is secured. Secured to the ends 14 for receiving the ends of a curler upon which the strand of hair is to be wound. The plate 13 is secured to the underlying bar 12 and is retained in spaced relationship therewith by means of pins 16 and 17.

Part 11 is similarly formed of an underlying rigid bar 18 to which the plate 19 is secured by means of pins 21 and 22. Pin 21 serves as a pivotal connection to the arms 23, which in turn are secured to the corresponding end of bar 12. In order to releasably clamp the other end of elements 10 and 11 together, I have shown spaced links 24 which are pivotally carried by pin 22. The free ends of links 24 are pivotally connected to a cam locking lever 26. The corresponding free end portion 25 of bar 12 is formed hook-shaped to enable engagement by the cam locking lever 26.

The gripping surfaces for the two elements 10 and 11 are formed by the members 27. These members are preferably duplicates and can be constructed as illustrated in detail in Figs. 4 and

5. Thus, each member is hollow and is formed entirely of resilient material, such as resilient vulcanized rubber. The side walls 29 are provided with outer, roughened faces 31, forming hair-gripping surfaces. The opening 32, extending entirely through the body, conforms substantially to the form of the bars 12 and 18. The wall 33 integrally connects the two side walls 29. The upper side of the body is provided with a longitudinal slit 34, thereby forming two resilient flanges 36. These resilient flanges or lips can be somewhat reinforced by integral rubber pads 37.

The resilient members 27 can be readily applied to or removed from the bars 12 and 18. Thus, as illustrated in Fig. 2, one member 27 is being applied upon the bar 12 by longitudinal sliding movement. During such application the walls of member 27 may be somewhat distorted,

as indicated, but when in final position extending between the pins 16 and 17, the member will assume its proper form, as indicated in Fig. 3. In applying a similar member to the bar 18 for element 11, it is necessary to first slip the member over links 24 and cam lock levers 26, while these elements are extended in line with the bar 18. Here again the member 27 will be somewhat distorted as it passes over links 24 and levers 26, but when in final position between the pins 21 and 22 its original form will be assumed. Removal of members 27 can be accomplished by sliding movement or by applying sufficient twisting force to bend back one of the lips 36.

With the members 27 properly positioned upon the elements 10 and 11, opposed surfaces 31 will be afforded which can be tightly clamped upon a strand of hair to afford an adequate grip. In the event these surfaces become somewhat deteriorated, whereby the desired grip is not afforded, they can be readily removed and reversed, and then, after again being positioned upon the protector, new gripping surfaces are afforded. If both gripping surfaces of a member 27 become worn or deteriorated, a new member of like construction can be readily substituted.

It is apparent from the above that I have provided a protector which is capable of a long useful life and which may be readily maintained in good operating condition. In marketing devices of this character, the members 27 can be sold as separate articles of manufacture for the purpose of making replacements. It will be noted that these members not only afford a proper grip upon the hair strand, but also, in conjunction with the other parts of the protector, afford a certain amount of heat insulation to prevent transmission of an undue amount of heat to the scalp. If a greater amount of heat insulation is desired, the lower faces of members 27 can be covered by strips 38 of heat insulating material such as felt (Fig. 6).

I claim:

1. In a hair waving protector, a pair of elements adapted to be clamped together upon opposite sides of a strand of hair to be waved, one of said elements including an elongated bar, a plate overlying the bar and extending parallel thereto in spaced relationship, means serving to connect both ends of the bar to the plate, and a hair gripping member removably embracing the bar and being formed entirely of resilient material, said gripping member being slit longitudinally on its upper side for substantially the entire length of the same. 5

2. In a hair waving protector, a pair of elements adapted to be clamped upon opposite sides of a strand of hair to be waved, one of said elements including an elongated bar and an overlying plate, both ends of the plate being secured in spaced parallelism to the bar by pins, and a hollow hair gripping member of resilient material removably embracing the bar, said member being removable with respect to the bar and having hair gripping surfaces formed on its two opposite side faces, the upper face of the member being slit longitudinally for its entire length. 25

3. In a hair waving protector, a pair of elements adapted to be clamped upon opposite sides of a strand of hair to be waved, each of said elements including an elongated bar and an overlying plate, each plate being secured to its associated bar in spaced parallelism, and hair gripping members of resilient material embracing the bars, said members each having duplicate hair gripping surfaces on its opposite side faces and having its upper side slit for substantially its entire length, to enable application to said bars by longitudinal sliding movement and to enable removal from said bars. 30 35
